MOTOR OPERATED TOOTHBRUSH HANDLE

Alfred W. Madl, Mequon, Wis., assignor to John Oster
Manufacturing Co., Milwaukee, Wis., a corporation of
Wisconsin

Filed Jan. 10, 1966, Ser. No. 547

Term of patent 14 years

(Cl. D9—2)

FIG. 1 is a front perspective view of a motor operated toothbrush handle embodying my new design;

FIG. 2 is a side elevational view thereof;

FIG. 3 is a rear elevational view thereof;

FIG. 4 is a top plan view thereof; and

FIG. 5 is a bottom plan view thereof.

The characteristic features of my design for the motor operated toothbrush handle disclosed reside in the manually-operated control actuator, provided on the body portion and in association with the concavely ribed panel feature thereof, having the configuration as shown.

The toothbrush shown in broken lines in FIG. 1 is for illustrative purposes only.

I claim:

The ornamental design for a motor operated toothbrush handle, as shown and described.
